UNITED STATES PATENT OFFICE

110,727

DESIGN FOR A HEADLIGHT TESTING INSTRUMENT OR SIMILAR ARTICLE

Charles W. MacMillan, Detroit, Mich., assignor to Hinckley-Myers Company, Jackson, Mich.

Application May 11, 1938, Serial No. 77,131

Term of patent 7 years

To all whom it may concern:

Be it known that I, Charles W. MacMillan, a citizen of the United States, residing at Detroit, in the county of Wayne and State of Michigan, have invented a new, original, and ornamental Design for a Headlight Testing Instrument or Similar Article, of which the following is a specification, reference being had to the accompanying drawing, forming part thereof.

Figure 1 is a plan view of a headlight testing instrument, showing my new design,
Figure 2 is a side view thereof, and
Figure 3 is a front perspective view thereof.

I claim:

The ornamental design for a headlight testing instrument or similar article, as shown.

CHARLES W. MACMILLAN.
